(57) **CLAIM**

The ornamental design for a coffee machine, as shown and described.

DESCRIPTION

FIG. 1 is a front perspective view of the coffee machine; FIG. 2 is another front perspective view thereof; FIG. 3 is a bottom perspective view thereof; FIG. 4 is a front view thereof; FIG. 5 is a rear view thereof; FIG. 6 is a left side view thereof; FIG. 7 is a right side view thereof; FIG. 8 is a top view thereof; and, FIG. 9 is a bottom view thereof.

In some implementations, the coffee machine, as shown in FIGS. 1, 3, and 7, includes a frother attached to a side of the body of the coffee machine. In some implementations, as shown in FIGS. 2 and 6, a side of the coffee machine includes an indentation configured to support a coffee machine tool (e.g., spoon). In some implementations, as shown in FIGS. 1-9, a front bottom side of the coffee machine includes a circular cup holder. In some implementations, the coffee machine, as shown in FIGS. 1-9, includes fins to access interior portions of the coffee machine.

The broken lines shown in the figures show features of the coffee machine that form no part of the claimed design.
